COMBINED TOOTHBRUSH HOLDER AND DRIER

Noah B. Jones, Brownsville, Pa.

Application December 16, 1957, Serial No. 48,903

Term of patent 14 years

(Cl. D4—3)

Fig. 1 is a perspective view of a combined toothbrush holder and drier showing my new design.

Fig. 2 is a side elevational view thereof showing the plug and part of the cord omitted for convenience of illustration.

Fig. 3 is a top plan view thereof showing the plug and part of the cord omitted for convenience of illustration.

The toothbrushes shown in broken lines are depicted for illustrative purposes only.

I claim:

The ornamental design for a combined toothbrush holder and drier, substantially as shown and described.
